LIQUID DISPENSING APPARATUS

Richard R. Trexler, Evanston, Ill.

Application December 9, 1942, Serial No. 468,362

15 Claims. (Cl. 222—28)

1

This invention relates to liquid dispensing apparatus, particularly of the type adapted for the dispensing of gasoline and the like.

It is an object of the invention to provide liquid dispensing apparatus of improved construction and operating characteristics, and more particularly to provide improved driving means therefor.

More specifically stated, it is an object of the invention to provide liquid dispensing apparatus of the meter pump type wherein improved transmission means is provided for connecting the meter pump in driving relation with its prime mover or propelling means. In accordance with the principles of the invention a fluid transmission is interposed between the meter pump and its propelling means, which fluid transmission is operable to transmit power between the propelling means and the meter pump while at the same time permitting the propelling means to operate independently of the pump as may be desired when the pump is operating at reduced speed or when the pump is stationary. While the invention has particular applicability to meter pump dispensing apparatus, obviously it also may be used in apparatus employing independent metering devices.

A further object of the invention is to provide liquid dispensing apparatus having a fluid transmission between the dispensing pump and its driving or propelling means, wherein means is provided for controlling the fluid transmission in accordance with the dispensing demands of the pump, and more specifically in accordance with the pressure conditions in the dispensing line on the outlet side of the dispensing pump, between the pump and the dispensing nozzle valve.

Various other objects, advantages and features of the invention will appear from the following specification when taken in connection with the accompanying drawings, wherein certain preferred embodiments of the invention are set forth for purposes of illustration.

In the drawings, wherein like reference numerals refer to like parts throughout:

Fig. 1 is a general assembly view of a liquid dispensing apparatus embodying and constructed in accordance with the principles of the invention, parts of the apparatus used being broken away to more clearly illustrate the elements of the structure;

Fig. 2 is a detail view of a baffle member adapted to be interposed between the dispensing line

2

and the fluid transmission in the apparatus illustrated in Fig. 1;

Fig. 3 is a detail sectional view of the fluid transmission mechanism as embodied in the apparatus of Fig. 1;

Fig. 4 is a detail view similar to Fig. 3, but illustrating a modified form of structure;

Fig. 5 is a general assembly view, similar to Fig. 1, but illustrating a further modified form 10 of fluid transmission or driving means; and

Fig. 6 is a detail view of the pressure controlled bellows and valve assembly as used in the embodiment of the invention illustrated in Fig. 5.

This application is a continuation-in-part of 15 my copending application, Serial No. 268,551, filed April 18, 1939, now Patent No. 2,390,136, December 4, 1945, entitled "Liquid dispensing apparatus."

Referring more specifically to the drawings, 20 and first to the embodiment of the invention illustrated in Figs. 1, 2 and 3, the dispensing apparatus shown comprises an upstanding housing 10 adapted to support and enclose the several elements of the apparatus, the apparatus being 25 associated with an underground supply tank or the like 11 forming a reservoir for the liquid 12 to be dispensed.

The dispensing apparatus comprises a main dispensing pump 13, the pump being connected 30 to the underground tank 11 by means of an inlet pipe 14 through which liquid is adapted to be drawn by the pump from the underground tank. Preferably the pump 13 is of the meter pump type, that is, it is preferably an accurate pump 35 structure wherein the movements of the pump parts are directly proportional to the quantities of liquid propelled therethrough. The use of a pump of this type renders it unnecessary to provide a separate metering mechanism to measure 40 the quantities of dispensed liquid.

The dispensed liquid is delivered by the pump 13 to an outlet pipe 15 connected to the usual sight gauge 16 and flexible hose 17 terminating in a dispensing nozzle 18. The dispensing nozzle 45 is controlled by a manually controlled dispensing valve of any suitable conventional type, as indicated at 19.

A gear 20 is connected to one of the operating pumping elements of the pump, this gear being 50 arranged to drive a worm member 21 connected to drive an elongated flexible transmission cable 22. At its upper end this transmission cable is arranged to drive a volume register 23 by means of a flexible chain 24, a shaft 25, bevel gearing 55 26 and a chain 27 connected to the volume reg-

ister. The transmission cable 22 is also adapted to drive a cost register 28 by means of a variator or change speed gearing 29 to which the cable 22 is connected at its upper end, which variator or change speed gearing is connected to the cost register by means of gearing 30, shaft 31 and a driving chain 32. By this means it will be seen that the gear 20, forming a part of the operating structure of the dispensing pump, is arranged to drive the volume and cost registers to indicate the volume and cost of the liquid dispensed. The variator or change speed gearing 29 may be adjusted so that the cost register is operated in accordance with the proper unit cost of the liquid or commodity.

The driving mechanism for the dispensing pump 13, forming the subject matter of the present invention, comprises an electric motor or other suitable prime mover 35. As shown, the motor is controlled by means of a switch 36 operated from a rod 37 connected to a nozzle support arm 38, the arrangement being such that when the support arm 38 is pivoted upwardly after removal of the nozzle 18 therefrom, the switch 36 is operated to energize the motor 35. The electric motor 35 is provided with a bevel driving gear 40 arranged in driving relation with a bevel gear 41 pinned to a shaft 42. This shaft forms the drive shaft for the fluid transmission, as will be best understood by reference to Fig. 3. The fluid transmission comprises a liquid filled cylindrically shaped housing 45 enclosing a driving propeller wheel 46 and a driven propeller wheel 47, the propeller wheels being provided with oppositely facing blades 48 in close juxtaposition when the wheels are in normal driving relation as illustrated in Fig. 3. The driving propeller wheel 46 is connected to the drive shaft 42 by means of a splined connection, the arrangement being such that the wheel is constrained for rotation with the shaft at all times, but may shift axially thereon through a predetermined range of movement. More specifically, the propeller wheel 46 is provided with a hub portion 49 embracing the shaft 42 and having a splined connection therewith. This hub rotates within a packing assembly 50 secured to and forming a part of the housing 45. Movement of the propeller wheel 46 away from the propeller wheel 47, or to the right as shown in Fig. 3, is limited by the engagement of the wheel against the inner end 51 of the packing structure. Movement of the wheel 46 toward the wheel 47, or to the left as shown in Fig. 3 is limited by the engagement of a collar 52, adjustably fixed to the sleeve 49 by means of a set screw 53, against the outer member 54 of the packing structure. A compression spring 55 arranged between the bevel gear 41 and the propeller wheel sleeve 49, normally urges the propeller wheel to the left into the position illustrated in Fig. 3.

The driven propeller wheel 47 of the fluid transmission is pinned to a driven shaft 58 provided on its end with a bevel gear 59. This bevel gear is in driving relation with a bevel gear 60 secured to a shaft 61, the lower end of which carries a bevel gear 62 in driving engagement with a bevel gear 63 connected to drive the operative pumping elements of the dispensing pump 13. A packing structure 64 is provided for the driven shaft 58, the two packing structures 64 and 50 permitting rotation of the propeller wheels and their associated driving and driven shafts, while maintaining a pressure and fluid tight seal for liquid within the housing 45.

A pipe line or conduit 65 is connected to the dispensing line 15, preferably adjacent the upper end thereof, this pipe line being connected to a pipe line 66 terminating within the casing or housing 45 of the fluid transmission. Preferably there is interposed between the pipes 65 and 66 a baffle device 67 shown in detail in Fig. 2. This baffle device comprises a pair of complementary plate members forming a pair of chambers 68 and 69, the plate members being arranged to clampingly engage a flexible diaphragm member 70 therebetween. The diaphragm member 70 prevents fluid communication between the pipes 65 and 66, while permitting fluid pressure transmission therebetween.

In operation, during dispensing and while the dispensing nozzle valve 19 is open, there is only a relatively low pressure in the dispensing line 15. Accordingly, only a correspondingly low pressure exists within the housing 45 of the fluid transmission, permitting the compression spring 55 to hold the propeller wheel 46 in its leftward position as shown in Fig. 3 in immediate juxtaposition to and in operating driving relation with the propeller wheel 47. Under such conditions, the two propeller wheels being held in operating driving juxtaposition, the fluid transmission unit acts as a hydraulic transmission or clutch transmitting power between the driving shaft 42 and the driven shaft 58, as will be understood by those skilled in the art. By this means, the electric motor 35 effects the driving of the dispensing pump 13.

As the nozzle valve 19 is closed at the end of the dispensing operation, pressure within the dispensing line builds up, and this pressure is transmitted through the pipes 65 and 66 to the liquid within the casing 45 of the fluid transmission. Due to the fact that there is a greater area of the propeller wheel 46 on the left side thereof exposed to the pressure within the casing 45, than on the right side thereof, the pressure within the casing 45 effects the automatic shifting of the propeller wheel 46 to the right against the action of the spring 55, thereby effecting the separation of the propeller wheels 46 and 47, and the breaking of the fluid driving connection therebetween. It will be seen that the driving force which may be transmitted through the fluid transmission varies with the spacing between the propeller wheels 46 and 47, which spacing is in turn dependent upon the pressure within the dispensing line 15. If the nozzle valve is completely closed, the propeller wheel 46 moves a maximum distance away from the driven propeller wheel 47 to effect a maximum reduction in the driving force of the transmission whereby to substantially unload the dispensing pump 13. On the other hand, if the nozzle valve is but partially closed whereby to effect liquid dispensing at reduced rates of flow, a partial rise of pressure takes place within the dispensing line 15 resulting in a partial separation of the propeller wheels 46 and 47.

By this means it will be seen that the fluid transmission maintains a proper driving relationship between the prime mover or motor 35 and the metering dispensing pump 13, permitting a proper driving relationship therebetween during dispensing operations, while at the same time permitting operation of the motor 35 independently of the pump 13, when the nozzle valve has been closed, or permitting the necessary relative slipping between the motor and the pump when dispensing at partial rates of flow. The motor

35 may accordingly operate at substantially constant speed during an entire dispensing operation, and while the nozzle support 38 is raised to energize the motor switch.

The baffle device 67 permits transmission of fluid pressures between the pipes 66 and 65, while effecting a separation of the liquids therebetween. Accordingly the liquid used within the casing 45 of the fluid transmission may be selected to best meet the requirements of the installation, and may for example be oil or the like. It is obvious, however, that the baffle device 67 may be omitted if desired, permitting the dispensed liquid to flow directly into the fluid transmission casing 45. To minimize whirling of the liquid within the casing 45, radially inwardly directed baffle plates as indicated at 75 may be provided. Obviously it is within the scope of the invention to provide a mounting for the propeller wheel 47 similar to that provided for the propeller wheel 46 whereby both propeller wheels effect a shifting away from each other upon increase of pressure within the casing 45, thereby effecting a further and more rapid separation between the propeller wheels, if desired.

In Fig. 4 a modified embodiment of the fluid transmission structure is provided. In this instance the pipe 66a communicating with the outlet dispensing line, instead of being directed to the interior of the casing 45a as in the embodiment previously described, is directed instead to a cylinder structure 77 supported on one of the end walls of the casing 45a. This cylinder is provided with a piston 78, the piston rod 79 of which is connected by means of a pin and slot connection with a lever 80 suitably pivoted upon a portion of the apparatus frame as indicated at 81. The lower end of the lever 80 is bifurcated to form a yoke having inwardly directed pins 82 adapted to ride within a groove 83 provided in a collar member 84. The collar 84 is rotatably mounted on the sleeve 49a of the driving propeller wheel, but constrained against longitudinal motion thereon by means of a pair of ball bearing collars 85 and 86 secured to the sleeve 49a on opposite sides of the collar 83.

As fluid pressure is introduced into the cylinder 77 through the pipe line 66a, the piston 78 is urged to the right as seen in Fig. 4, thereby effecting the rightward shifting of the sleeve 49a and its associated driving propeller wheel 46a for the purpose previously described in reference to Fig. 3. In the embodiment of Fig. 4 a baffle device 67 such as previously described may or may not be provided in association with the pipe 66a, as may be desired.

In Figs. 5 and 6 a still further embodiment of fluid transmission is provided. In this instance the dispensing pump 13b, similar in purpose and function to the pump 13 previously described in reference to the embodiment of the invention shown in Fig. 1, is arranged to be driven by a fluid or hydraulic transmission comprising a pair of pumps 90 and 91 interposed between the motor 35b and the metering dispensing pump 13b, the pump 91 being adapted to operate as a fluid or hydraulic motor.

More specifically, the motor 35b is in this instance arranged by means of bevel gearing 92, 93, a shaft 94, and bevel gearing 95, 96 to drive the pump 90, which may for example be a gear pump or the like. This pump 90 is adapted to circulate fluid or liquid, preferably oil, within a closed circuit comprising the pipes 97 and 98. These pipes connect the pumps 90 and 91 so

that as the pump 90 is driven, the pump 91 is correspondingly operated as a fluid or hydraulic motor. The pump 91 is arranged by means of bevel gearing 99, shaft 100, and bevel gearing 101 to operate the main metering dispensing pump 13b.

A pair of pipes 102 and 103 form a by-pass circuit between the pipes 97 and 98, the connection between the pipes 102 and 103 being controlled by means of a valve 104 shown in detail in Fig. 6. This valve is so arranged that when it is in the position shown in Fig. 6 fluid communication between the pipes 102 and 103 is blocked. However, when the valve piston 105 is lowered communication between the pipes 102 and 103 is established by valve piston channels 106, 107 and 108.

To operate the valve, the piston 105 is connected by means of a rod 110 with a bellows structure 111. This bellows structure is provided with a flexible bellows element 112, the upper end of which is connected by means of a plate 113 to the rod 110; the lower end of the bellows being sealed to the housing in a fluid tight joint as indicated at 114. A compression spring 115 normally urges the rod 110 upwardly into the position shown in Fig. 6, but when fluid pressure is introduced into the bellows structure by means of the pipe 116, the bellows is collapsed and the rod 110 is forced downwardly to open the valve against the action of the spring 115. The pipe 116 is connected to the dispensing line 15b as in the embodiment of the invention shown in Fig. 1.

A pipe line 117 also forms a by-pass connection 35 between the pipes 97 and 98, the circulation of fluid within the pipe 117 being controlled by an adjustable spring pressed relief valve 118 which may be of conventional structure.

In operation, when the motor 35b is operating 40 and the dispensing valve 19b is open, pump 90 is driven and by means of the liquid circulation within the pipes 97 and 98, the pump 91 is correspondingly driven as a fluid motor which effects the operation of the main metering dispensing 45 pump 13b. The pumps 90 and 91 and their associated conduits thus form a fluid transmission connecting the motor 35b and the dispensing pump 13b as in the previously described embodiment of the invention. As the nozzle valve 19b is 50 partially closed, pressure is correspondingly partially or fully built up within the dispensing line 15b and within the bellows structure 111, thereby effecting a partial or full opening of the valve structure 104. When the valve 104 is open, the 55 fluid pumped by the pump 90 is by-passed between the pipes 97 and 98 by means of the pipes 102 and 103 and accordingly the pump 91 may be stopped, as when the dispensing valve 19b is fully closed, or slowed down, as when the dispensing 60 valve 19b is partially closed, as may be required. The valve 118 which may be adjustably set to any predetermined pressure, acts as a safety valve permitting the by-passing of fluid between the pipes 97 and 98 in the event the valve 104 fails. 65 It is obvious that various changes may be made in the specific embodiments of the invention set forth for purposes of illustration without departing from the spirit of the invention. Accordingly the invention is not to be limited to the specific 70 embodiments shown and described, but only as indicated in the following claims.

The invention is hereby claimed as follows:

1. A liquid dispensing apparatus comprising a dispensing line adapted to be connected to a source of liquid supply, a dispensing pump ar-

ranged in said dispensing line for propelling liquid therethrough, a prime mover for operating the pump, a fluid transmission connecting the prime mover and pump in operating driving relationship, and means controlled by the dispensing line pressure for controlling the action of the fluid transmission, said fluid transmission comprising fluid propelling means and a fluid propelled thereby, and means for isolating the transmission fluid from the liquid propelled by the dispensing pump.

2. A liquid dispensing apparatus as defined in claim 1, wherein said fluid transmission comprises a circulating pump driven by the prime mover, a fluid motor connected to drive the dispensing pump, and means connecting the fluid motor and the circulating pump in a fluid circuit whereby to effect a driving relation therebetween.

3. A liquid dispensing apparatus comprising a dispensing line adapted to be connected to a source of liquid supply, a pump arranged in said dispensing line for propelling liquid therethrough, a prime mover for operating the pump, means comprising fluid propelling mechanism and a fluid propelled thereby forming a fluid transmission connecting the prime mover and pump in operating driving relationship, and means controlled by the pressure in the dispensing line for varying the operative effectiveness of said fluid transmission, while maintaining a constant fluid level within the fluid transmission.

4. A liquid dispensing apparatus comprising a dispensing line adapted to be connected to a source of liquid supply, a pump arranged in said dispensing line for propelling liquid therethrough, a prime mover for operating the pump, means forming a fluid transmission connecting the prime mover and pump in operating driving relationship, and means automatically operable in accordance with the delivery demands upon said pump for varying the operative effectiveness of said fluid transmission.

5. A liquid dispensing apparatus comprising a dispensing line adapted to be connected to a source of liquid supply, a pump arranged in said dispensing line for propelling liquid therethrough, a prime mover for operating the pump, means forming a fluid transmission connecting the prime mover and pump in operating driving relationship, and means controlled by the pressure in the dispensing line for controlling the operative effectiveness of said fluid transmission.

6. A liquid dispensing apparatus comprising a dispensing line adapted to be connected to a source of liquid supply, a pump arranged in said dispensing line for propelling liquid therethrough, a prime mover for operating the pump, means forming a fluid transmission connecting the prime mover and pump in operating driving relationship, said fluid transmission comprising a housing, a liquid bath within the housing, and a pair of propeller wheels arranged within the liquid bath whereby rotational movements of one of said propeller wheels are transmitted to the other through the liquid bath, and means for shifting the propeller wheels relative to each other for varying the operative effectiveness of the driving connection therebetween.

7. A liquid dispensing apparatus as defined in claim 6, wherein means is provided automatically operable in accordance with the delivery demands upon said pump for actuating said shifting means.

8. A liquid dispensing apparatus as defined in claim 6, wherein means is provided automatically

operable in accordance with the pressure within the dispensing line for actuating said shifting means.

9. A liquid dispensing apparatus comprising a dispensing line adapted to be connected to a source of liquid supply, a pump arranged in said dispensing line for propelling liquid therethrough, a prime mover for operating the pump, means forming a fluid transmission connecting the prime mover and pump in operating driving relationship, said fluid transmission comprising a housing, a liquid bath within the housing, and a pair of propeller wheels arranged within the liquid bath whereby rotational movements of one of said propeller wheels are transmitted to the other through the liquid bath, a pipe connecting the dispensing line and said housing, and at least one of said propeller wheels being adjustably mounted with respect to the other propeller wheel and being provided with a differential area exposed to said liquid bath whereby a variation of pressure within the housing effects a shifting of said propeller wheel.

10. A liquid dispensing apparatus comprising a dispensing line adapted to be connected to a source of liquid supply, a pump arranged in said dispensing line for propelling liquid therethrough, a prime mover for operating the pump, means forming a fluid transmission connecting the prime mover and pump in operating driving relationship, said fluid transmission comprising a housing, a liquid bath within the housing, and a pair of propeller wheels arranged within the liquid bath whereby rotational movements of one of said propeller wheels are transmitted to the other through the liquid bath, and means comprising a pressure device operable externally of said housing for shifting said propeller wheels relative to each other whereby to vary the operative driving relation therebetween.

11. A liquid dispensing apparatus comprising a dispensing line adapted to be connected to a source of liquid supply, a dispensing pump arranged in said dispensing line for propelling liquid therethrough, a prime mover for operating the dispensing pump, means forming a fluid transmission connecting the prime mover and dispensing pump in operating driving relationship, said fluid transmission comprising a circulating pump driven by the prime mover, a fluid motor driven by the circulating pump, said fluid motor being arranged to drive the dispensing pump pipes connecting the circulating pump and the fluid motor in a closed circuit, a by-pass connection between said pipes, and a valve controlled by the pressure within the dispensing line for controlling said by-pass connection.

12. A liquid dispensing apparatus comprising a dispensing line adapted to be connected to a source of liquid supply, a pump arranged in said dispensing line for propelling liquid therethrough, a prime mover for operating the pump, means forming a fluid transmission connecting the prime mover and pump in operating driving relationship, said fluid transmission comprising a housing, a liquid bath within the housing, and a pair of propeller wheels arranged within the liquid bath whereby rotational movements of one of said propeller wheels are transmitted to the other through the liquid bath, and means for maintaining a substantially constant liquid level of said liquid bath within the housing.

13. A liquid dispensing apparatus comprising a dispensing line adapted to be connected to a source of liquid supply, said dispensing line ter-

minating in a nozzle having a control valve for controlling the flow of liquid within the dispensing line, a pump arranged in said dispensing line for propelling liquid therethrough, a prime mover for operating the pump, means forming a fluid transmission connecting the prime mover and pump in operating driving relationship, and means operable in accordance with the opening of the nozzle valve for controlling the operative effectiveness of said fluid transmission.

14. A liquid dispensing apparatus comprising a dispensing line adapted to be connected to a source of liquid supply, said dispensing line terminating in a dispensing nozzle having a control valve for controlling liquid flow within the dispensing line, a pump arranged in said dispensing line for propelling liquid therethrough, a prime mover for operating the pump, means forming a fluid transmission connecting the prime mover and pump in operating driving relationship, said fluid transmission comprising a housing, a liquid bath within the housing, and a pair of propeller wheels arranged within the liquid bath whereby rotational movements of one of said propeller wheels are transmitted to the other through the liquid bath, and means controlled in accordance with the opening of said nozzle valve for shifting the propeller wheels relative to each other for varying the operative effectiveness of the driving connection therebetween.

15. A liquid dispensing apparatus comprising a dispensing line adapted to be connected to a source of liquid supply, a pump arranged in said

dispensing line for propelling liquid therethrough, a prime mover for operating the pump, means forming a fluid transmission connecting the prime mover and pump in operating driving relationship, said fluid transmission comprising a housing, a liquid bath within the housing, and a pair of propeller wheels arranged within the liquid bath whereby rotational movements of one of said propeller wheels are transmitted to the other through the liquid bath, and means for shifting the propeller wheels relative to each other for varying the operative effectiveness of the driving connection therebetween, said shifting means comprising a liquid conduit connecting the dispensing line and said housing whereby pressure conditions within the dispensing line are transmitted to the housing, and baffle means arranged within the conduit whereby the liquid in the housing is isolated from the liquid in the dispensing line.
